COPING FOR A SWIMMING POOL WALL

Leslie N. Jefferson, Rte. 3, Box 357,
Canby, Oreg. 97013

Filed May 3, 1968, Ser. No. 11,768

Term of patent 14 years

U.S. Cl. D13—1
Int. Cl. D25—01

Fig. 1

I claim:

The ornamental design for coping for a swimming pool wall, substantially as shown and described.
